UNITED STATES PATENT OFFICE.

CLARENCE L. TAYLOR AND EDGAR E. BROSIUS, OF ALLIANCE, OHIO, ASSIGNORS TO THE MORGAN ENGINEERING COMPANY, OF ALLIANCE, OHIO.

LADLE OR DOUBLE-TROLLEY ELECTRIC CRANE.

No. 920,215.

Specification of Letters Patent.

Patented May 4, 1909.

Application filed February 21, 1908. Serial No. 417,211.

To all whom it may concern:

Be it known that we, CLARENCE L. TAYLOR and EDGAR E. BROSIUS, of Alliance, in the county of Stark and State of Ohio, 5 have invented certain new and useful Improvements in Ladle or Double-Trolley Electric Cranes; and we do hereby declare the following to be a full, clear, and exact description of the invention, such as will 10 enable others skilled in the art to which it appertains to make and use the same.

Our invention relates to an improvement in ladle or double trolley electric cranes, and more particularly to an improvement on 15 that type of ladle cranes in which the main trolley is supported upon split or divided main girders with the hoisting chains passing downwardly between the two sections of such split or divided main girders. Heretofore in the construction of this type of ladle crane the main trolley has been provided with equalizing trucks for distributing the weight of the main trolley and load carried thereby equably on the four sections of the 20 main girder. Such equalizing trucks have added to the cost and weight of the main trolley and the object of our invention is to dispense with equalizing trucks and thereby simplify and cheapen the construction of 25 30 this type of crane.

With these objects in view our invention consists in the features of construction and combinations of parts hereinafter described and pointed out in the claims.

35 In the accompanying drawings, Figure 1 is a view partly in side elevation and partly in transverse section of a ladle crane embodying our invention. Fig. 2 is a plan view of the same. Fig. 3 is a view in plan 40 and Fig. 4 an end view of a modification.

The main girders each consist of the two web girders 1, 2, which are connected at their ends to the end girders of the bridge crane. The main girder sections 1, 2, are 45 each provided with the usual flanges 4 and with the track-rails 5, 5^a, upon which are supported the double-flanged wheels 6, 7, mounted in the frame of the main trolley. Inside of the main girders are located the 50

auxiliary girders 8, 8, which are provided with rails 9, 9, for the support of the auxiliary trolley 10. The auxiliary girders are connected with the inner sections of the main girders by horizontal lacing bars 11, 12 to insure the requisite lateral stiffness and rigid-

ity to the auxiliary girders and the inner sections of the main girders. The hoisting drums 13, 14, of the main trolley are located at its opposite sides and are arranged parallel to the girders with the main hoisting ropes 60 15, extending downwardly from said drums between the narrow opening between the two sections of the main girder and through the sheave or block connected with the ladle carrying bar and thence upwardly over the 65 grooved pulleys 16, 17, and from thence downwardly to the ladle carrying bar. Thus it will be seen that the fleet of the main hoisting ropes is in a line parallel to the main girders and hence a narrow space between 70 such girders suffices for the proper operation of the main hoisting ropes.

At each end of the main trolley frame are journaled in suitable bearings the supporting wheels 6 and 7, the wheels 6 being 75 mounted on rails 5 and the wheels 7 being mounted on the rails 5^a. Owing to the fact that these supporting wheels are located at the four corners of the main trolley frame, the latter will afford sufficient flexibility 80 to permit the weight of the main trolley and the load carried thereby to be equally distributed to the four sections of the girders which constitute the two main girders. This construction is simple and efficient and 85 renders unnecessary the use of transversely operating equalizing trucks.

Figs. 3 and 4 represent a modification for use in cranes of large capacity and in which it is desirable to distribute the weight of the 90 main trolley and load carried thereby over a greater surface or extent of the main girders or tracks supported thereby, and to accomplish this the main trolley frame is supported at each end by swiveled trucks 18, 19, 95 which are arranged parallel with the girders, as is clearly shown in the drawings. The wheels on the outer swiveled trucks run upon the rails of the outer sections of the main girders while the wheels of the inner swiveled trucks located on the opposite side of the main trolley frame run upon the rails mounted upon the inner sections of the main girders.

100 It is evident that many slight changes in the construction and arrangement of the parts of our improvement might be varied without departing from the invention and hence we would have it understood that we do not restrict ourselves to the particular 110

construction and arrangement of parts shown and described, but,—

Having fully described our invention what we claim as new and desire to secure by Letters-Patent, is:

1. In a ladle or double trolley crane, the combination with divided main girders, of the main trolley mounted on said girders, each end of the trolley being supported at 10 one corner on one section only of a girder, and at its opposite corner on the other section only of the same girder.

2. In a ladle or double trolley crane, the combination with split or divided main girders, of a main trolley provided with 15 hoisting ropes extending downwardly between the sections of the main girders, each end of the trolley being supported at one corner on one section only of a girder, and

at its opposite corner on the other section 20 only of the same girder.

3. In a ladle or double trolley electric crane, the combination with split or divided main girders, of a main trolley provided at one side with supporting wheels which are 25 wholly supported by the outer sections of the main girder and at its opposite sides with wheels which are supported wholly by the inner sections of the main girders.

In testimony whereof, we have signed this 30 specification in the presence of two subscribing witnesses.

CLARENCE L. TAYLOR.
EDGAR E. BROSIUS.
